Geo. O. Sanderson

United States Patent Office.

GEORGE O. SANDERSON, OF BOSTON, MASSACHUSETTS.

Letters Patent No. 63,815, dated April 16, 1867.

IMPROVEMENT IN GAS COOKING STOVES.

The Schedule referred to in these Letters Patent and making part of the same.

TO ALL WHOM IT MAY CONCERN:

Be it known that I, GEORGE O. SANDERSON, of Boston, in the county of Suffolk, and State of Massachusetts, have invented an Improvement in Cooking Stoves; and I do hereby declare that the following is a full and exact description thereof, reference being had to the accompanying drawings and to the letters of reference marked thereon.

Nature.

The nature of my invention consists in the construction and arrangement of the parts of a cooking stove or range so that the stove may be used for burning solid fuel or gas.

To enable others skilled in the art to make and use my invention I will proceed to describe its construction and use.

Drawings.

Figure 1 represents a perspective view of the stove complete, with the fuel grate removed and the gas pipes inserted.

Figure 2 is a longitudinal vertical section of the same.

Figure 3 is a front elevation of the same.

Figure 4 is a plan of the same.

Figure 5 is a full-sized drawing, representing in elevation the stop-cock for turning on the gas, and also the arrangement for mixing atmospheric air with the gas. For the purpose of enhancing its heating power the position of the stop-cock and mixing arrangement is indicated by H, figs. 1, 2, and 3.

A A, figs. 1, 2, 3, and 4, represent a wood, coal, or peat cooking stove, made in any of the ordinary forms, but here represented with the grate for solid fuel removed and pipes for gas inserted in its place. N represents the main supply pipe for admission of gas to the stove. To this pipe N is attached the pipe O by suitable couplings. To the upper end of the pipe O the horizontal pipe M is attached, from which the pipes P' P'' lead to the pot holes B B', fig. 1, and also the pipes E E', leading to the rear pot holes C C. The upper or discharge ends of these pipes are flattened, as shown in figs. 2 and 4, so that the mixed gas and air can only escape through a narrow slit, formed by the flattened end of the pipe. The ends of the pipes are flattened, as above described, so that the flame shall not follow the gas down into the pipes. At H H, in all these pipes, the stop-cock and mixer represented in fig. 5 are inserted. The stop-cock H, fig. 5, is made in the ordinary manner. The gas enters the mixer through the small orifice represented by the dotted line Q, fig. 5, and passes by the openings R R up into the pipe P'; at the same time the atmospheric air enters the openings R R, and thus the two become mixed in the pipe P'. The front pot holes are provided with shallow basins B B', through the bottom of which the gas pipes P' P'' enter. The rear pot holes are provided with rings or short cylinders reaching from the top of the stove to the top of the oven. Into the sides of these cylinders the gas pipes E E' enter. The products of combustion are taken from B B', through the pipes F F, to the rear pot holes C C, from which they escape through the opening shown in the lower part of the cylinder D D, figs. 1 and 2. The object of the shallow basins B B' and the short cylinders C C is to confine the heat of the blazing gas immediately to the vessel resting upon the pot holes. The oven is heated by a series of pipes G G, figs. 1, 2, and 3, all of which are supplied with the stop-cock and mixer represented in fig. 5.

Use.

To use solid fuel in my stove, all of the gas pipes are unscrewed from each other and laid away for future use. The openings through which the ends of the pipes G G pass are protected by a thin metal slide. The grate is inserted, resting upon the bar I, figs. 1 and 3. The shallow basins B B' and the short cylinders D D are removed, and the stove is now ready for solid fuel. To prepare the stove for gas the grate is to be removed and the pipes reinserted. The shallow basins B B' and D D are placed in the pot holes and the stove becomes a gas burner.

The advantages that I claim for my stove are that it may be changed from a solid fuel burner to a gas burner, or *vice versa*, by a few moments' work.

Claim.

What I claim as my invention, and desire to secure by Letters Patent, is—

1. The combination and arrangement of the pipes G G with the oven L, substantially as described and for the purpose set forth.
2. The combination of the basins B B' with the pot holes of the cooking stove, substantially as described and for the purpose set forth.
3. The combination of the short cylinders D D with the rear pot holes and the top of the oven, substantially as described and for the purpose set forth.

GEO. O. SANDERSON.
